UNITED STATES PATENT OFFICE.

WILLIAM DALBERG, OF DEARY, IDAHO.

OVERSHOE HOLDER.

Application filed February 15, 1921. Serial No. 445,205.

To all whom it may concern:

Be it known that I, WILLIAM DALBERG, a citizen of the United States, residing at Deary, in the county of Latah and State of Idaho, have invented new and useful Improvements in Overshoe Holders, of which the following is a specification.

An object of this invention is the production of simple, cheap and efficient means for holding an overshoe on a walking shoe.

Other objects will present themselves as the nature of the invention is better understood, reference being had to the accompanying drawings.

15 In the drawings:—

Figure 1 is a view illustrating the application of the improvement.

Figure 2 is a perspective view of the improvement.

20 Figure 3 is a view of the blank from which the improvement is formed.

Figure 4 is a view of a modification.

Figure 5 is a plan view of a still further modification.

25 Figure 6 is an edge view thereof.

Figure 7 is a sectional view approximately on the line 7—7 of Figure 5.

Figure 8 is a view of the blank from which the slide is formed.

30 Figure 9 is a detail sectional view on the line 9—9 of Figure 5.

In the preferred embodiment of the improvement, illustrated in Figures 1 to 3 of the drawings, the body of the overshoe holder is constructed from a single strip of suitable material, metal preferred.

As disclosed in Figure 3 of the drawings, the strip 1, near the ends thereof is bulged or punched outwardly so that when the strip is bent centrally upon itself to provide the spring arms 2 and 3, the convexed bulged portion 4 on the arm 2 will be received in the concavity provided by the bulged portion 5 of the arm 3. Thus the element 4 provides a head and the bulged portion 5 provides a socket to receive the head.

45 The strip 1, on the arm 2 thereof is slotted transversely and longitudinally, and the metal bounded by the said slot is bent outwardly forming a bendable finger 6. The arm 3 is provided with an elongated slot 7 that is designed to align with the slot 8 from which the finger 6 has been projected. In these registering 50 slots is the shank 9 of a rivet. The opposite

ends of the rivet are headed as at 10. The arms 2 and 3 normally assume an outward angle, away from each other from the centrally bent portion to the strip from which the arms extend, and it is manifest that by 60 sliding the headed stud 9 outwardly, or through the free end of the arms 2 and 3, the said arms will be brought together, so that the headed element 4 of the arm 2 will be received in the pocket 5 of the arm 3. By this arrangement the overshoe 11 can be 65 effectively clamped between the arms 2 and 3.

The finger 6 is bent on itself, as at 12, and continued substantially in the plane of the 70 portion thereof which is connected to the strip, so that the outer end of the finger thus provides a hook 13. This hook is designed to be brought over the upper edge of a shoe 14 as illustrated in Figure 1 of the 75 drawings.

As the strip 1 is comparatively long and as the finger 6 is bendable so that the hook may be formed on various parts thereof, it will be seen that the device is of an adjustable nature, so that it will efficiently support or hold overshoes on walking shoes of various heights.

80 In Figure 4 of the drawings, the overshoe engaging element may be substantially similar to that previously described, the same including spaced arms 15 and 16. The arms 15 and 16, as is true of the arms 2 and 3, in reality provide the jaws for the body member of the device. Swiveled on the connecting element for the arms 15 and 16 is a flexible element such as a chain 18, and the said chain has at its outer end a hook 19 that is designed to be arranged over the top 85 of the walking shoe.

90 In the remaining figures of the drawings, the finger 20 is constructed from a flat piece of metal and has one of its ends bent upon itself to provide a tongue 21 that is designed to be arranged over the top of a shoe. The plate 20 is provided with a longitudinal slot 23, the walls of which having opposed 95 transverse notches 24.

100 The overshoe holder is constructed of a strand of spring metal to include parallel arms 25 and a rounded connecting portion 26 for the arms. The arms are designed to exert a tension away from each other and are both provided with elongated longitudinal slots 28. The arms 25, outward of the 105

slots, and adjacent to the ends thereof are formed one, on its inner face with a lug 29 and the other with a hole 30 to receive the arms when the latter are forced toward each other.

The numeral 31 designates a slide for compressing the arms 25 toward each other or for permitting the expansion of the said arms. The slide, as disclosed in Figure 8 of the drawings is constructed from a single blank of metal, to include a body proper, indicated by the numeral 32, and oppositely projecting longitudinally extending tongues 33 and 34 respectively. The tongue 34 is of a materially less length than the tongue 33, the said tongue 33 having adjacent the end thereof a lateral enlargement providing a disk-like head 35. The body 32 is designed to be bent on the score lines 36, Figure 8, over the sides of the arms 25. The tongues are passed through the slots 28 in the arms, the head 35 being arranged on the lower arm 25 transversely of the slot 28 therein. The remaining portions of the tongue 33 are then bent upwardly through the slots, and the tongue 34 is bent downwardly through the slots. It will be apparent that by moving the slide toward the connected end 26 of the arms 25, the arms will spread away from each other and by moving the said slide in an opposite direction the arms will be forced toward each other.

Secured to one of the arms 25, at the body end 26 thereof is one arm of a U-shaped

member 36, the second arm 37 exerting a spring tension against the second arm 25. The plate or finger 20 may be turned right angularly to the U-shaped member, when the latter is arranged in one of the notches 24, and the said plate moved to arrange the U-shaped member in any of the other notches 24, and in this manner, the overshoe holder is adjusted with respect to the shoe proper.

Having described the invention, I claim:

In a means for holding an overshoe on a shoe, a plate provided with a longitudinal slot disposed through its center thereof, the walls of said slot having opposed transverse notches forming rounded apertures thereby, a tongue provided at one end of said plate and formed thereon by said end being bent upon itself, a U-shaped member adjustably secured to the opposite end of said plate, a strip which is centrally bent upon itself to provide angularly disposed resilient jaws, a lug disposed on the inner face of one of the jaws, a cup-shaped depression formed on the other jaw and designed to receive said lug, slidable adjusting means between the jaws contacting with the outer faces thereof, said U-shaped member having one of its arms secured to said strip and its other arm engaging the body portion of said strip for the purpose specified.

In testimony whereof I affix my signature.

WILLIAM DALBERG.
